UNITED STATES PATENT OFFICE.

WILLIAM HARLEY SANDERSON, OF DAYTON, OHIO.

PLATFORM-SCALE.

No. 825,279.

Specification of Letters Patent.

Patented July 3, 1906.

Application filed August 21, 1902. Renewed January 22, 1906. Serial No. 297,220.

To all whom it may concern:

Be it known that I, WILLIAM HARLEY SANDERSON, a citizen of the United States, residing at Dayton, in the county of Montgomery and State of Ohio, have invented certain new and useful Improvements in Platform-Scales, of which the following is a specification, reference being had therein to the accompanying drawings.

10 The invention relates to improved means for connecting the platform, such as that of an ordinary platform-scale, with the lever system, so that such platform, with its load, is suspended from the lever system by connections universally movable as distinguished from being supported on the lever system by bearings which are rigid with the platform.

15 The platform-suspending means when constructed according to my invention allows the platform to gravitate freely and to find its equilibrium of support in that central or normal position which is necessary to secure reliability in the action of the scale in the process of weighing.

20 The useful objects attained by the improvement are, among others, a low support of those bearing-surfaces which are rigid with the platform relative to the lever system, the said bearing-surfaces of the platform being 25 below the knife-edges of the lever system which carry the platform and its load; such a free suspension of the platform on the lever system as allows the platform to seek by gravity its normal and central position; to 30 secure greater accuracy in the weighing operation; to do away with the necessity of check-links or chains to maintain the platform in its normal position and prevent its horizontal displacement relative to the lever 35 system, and in such a suspended platform-scale to allow of the convenient assembling and separation of parts as may be required in manufacture, packing for shipment, reassembling, &c.

40 The invention consists in the parts and combinations thereof hereinafter set forth.

In order to make the invention more clearly understood, I have shown in the accompanying drawings means for carrying the 45 same into practical effect without limiting my improvements to the particular construction which I have shown for the purpose of illustration.

In said drawings, Figure 1 is a vertical sectional view of so much of a platform-scale as is necessary for an understanding of the in-

vention, the platform and its suspension means being shown in elevation. Fig. 2 is a top plan view of the same, partly broken away. Fig. 3 is an elevation, on a larger scale, of one of the spider-legs and connected parts. Fig. 4 is a plan view of the bearing-piece with its supported links in section.

Referring to the drawings, J indicates a suitable frame, such as a metallic casting, 5 adapted to contain and support the lever system and having at its top an opening or openings j under the platform to allow the free passage of portions of the platform to their connections with the lever system. 10 The latter comprises two levers H H', combined in the usual manner to receive the weight of the platform and its load at four points and adapted to transmit the desired proportion of such weight to the scale-beam 15 through a link H². The said levers are provided with knife-edges I', which are suspended by links E from staples f, attached to the upper part of the frame J. All of the above-mentioned parts may be of any preferred and 20 suitable construction.

The platform comprises a load-receiving plate D, connected with a spider A, as by pins d, which latter may be surrounded by rubber washers d', interposed between the 25 plate D and the spider. The spider A is adapted to transmit its load to knife-edges I of the lever system at four points; but instead of being provided with the usual rigid bearing-surfaces resting on the knife-edges I 30 said spider has those bearing-surfaces A' which are rigid with it arranged at some distance below said knife-edges. They are shown in the form of downwardly-directed and rounded or knife-edged hooks, the rear 35 portions a' of which are secured to the bifurcations or legs a of the spider by screws a². The bifurcated legs of the spider are made longer than usual to bring the surfaces A' to the desired distance below the knife-edges I. 40 At a² the parts a' are provided with flanges or shoulders abutting against the inner surfaces of the leg portions a.

B is a freely-movable bearing-block, preferably in the form of a saddle and having a 45 suitably recessed or curved surface b, adapted to rest on the knife-edge I. At each side of the latter it is further provided with bearing-surfaces b' and beyond the latter with flanges or heads b².

b³ is a rounded lateral extension which limits the position of the bearing B on the

knife-edge I relative to the lever system. The bearing is somewhat elongated in the direction of the length of the knife-edge to give sufficient length of bearing, as seen in Fig. 4.

5 c indicate links resting and freely movable on the bearings b', one at each side of the knife-edge and at their lower ends loosely or freely engaged with the bearing-surfaces A'.

The suspension means above described 10 gives at four points a support to the platform below the knife-edges of the lever system, such support or supports being freely movable in all directions horizontally within limits, enabling the platform to assume by 15 gravity that position which is desired and which is essential for an accurate performance of the functions of the scale and to resume or swing back to such position after any lateral displacement.

20 The links c are retained in position during any separation of the spider from the lever system by keeper-plates A², which are held beneath the parts a' by the heads of the screws a² or other suitable fastening and have extensions a⁴ beneath the lower ends of the links. Said extensions inclose or partly inclose the hooks with which the lower ends of the links engage and keep the latter in such engagement. The extensions a⁴ are preferably of 25 spring metal, so that the links may be inserted into place or removed by slightly pressing the extensions outward or downward. The upper ends of the two links c are retained in place on the bearing B between its 30 central elongated portion and the flanges b². The distance between the inner ends of the parts A' is such as will allow them to pass freely up at the sides of the knife-edge I when it is desired to remove the spider from the 35 lever system.

I am aware that suspension-bearings have heretofore been employed in the lever systems of scales and do not claim the same broadly, my invention relating to the application of suspension-bearings directly between 45 the platform or its spider and the lever system, so that the weight comes initially upon the lever system through suspension means at more than two weight-distributing points.

50 For the adjusting and leveling of the spider the bearings A' may have inserted beneath them one or more thin washers A⁴. By changing these washers for others of different thicknesses the bearings may all be regulated 55 to the required height.

What I claim is—

1. In a platform-scale, the combination with the platform, the downwardly-extending supports arranged in pairs, projections extending toward each other on each pair of 60 supports and an upwardly-extending link embracing each projection, of a saddle-bearing loosely mounted in each pair of links, said bearings being curved upwardly and widened transversely between the links, a 65 frame, platform-levers pivotally supported by the frame and knife-edge bearings on the levers projecting into the upwardly-curved and transversely-widened portions of the bearings; substantially as described. 70

2. In a platform-scale, the combination with the platform, the downwardly-extending supports arranged in pairs, hook-like projections extending toward each other on each pair of supports and an upwardly-extending 75 link embracing each projection, of a saddle-bearing loosely mounted in the upper end of each pair of links, said bearings having headed ends outside of the links, and upwardly-curved transversely-widened portions 80 between the links, a frame, platform-levers pivotally supported by the frame and knife-edge bearings projecting transversely from the levers and extending into the transversely-widened and upwardly-curved bearings; substantially as described. 85

3. In a platform-scale, the combination with the platform, the downwardly-extending supports arranged in pairs, detachable hook-like projections mounted on and having 90 shoulders resting against the inner face of each support, an upwardly-extending link embracing each projection, of a saddle-bearing loosely mounted in the upper end of each pair of links, and having upwardly-curved 95 and transversely-widened portions between the links and above the hook-like projections, a frame, platform-levers pivotally supported on the frame and knife-edge bearings projecting transversely from the levers and extending into the transversely-widened and upwardly-curved bearings; substantially as described. 100

In testimony whereof I affix my signature in presence of two witnesses.

WILLIAM HARLEY SANDERSON.
